UNITED STATES PATENT OFFICE.

JOHN SMITH, OF COLUMBUS, OHIO, ASSIGNOR TO THE CHAMPION DASH COMPANY, OF SAME PLACE.

BEAD FOR DASH-BOARDS OF CARRIAGES.

SPECIFICATION forming part of Letters Patent No. 249,801, dated November 22, 1881.

Application filed July 25, 1881. (No model.)

To all whom it may concern:

Be it known that I, JOHN SMITH, a citizen of the United States, residing at Columbus, in the county of Franklin and State of Ohio, have invented new and useful Improvements 5 in Binding Beads for Dash-Boards of Carriages, of which the following is a specification.

My invention relates to means for protecting the edges of vehicle dash-boards; and for this purpose I provide the dash with a tongued bead-edge or rim of sole-leather, india-rubber, gutta-percha, or any other hard material capable of being sewed and of receiving a polish, secured to the dash-leathers around the 15 metallic frame by stitching.

In the accompanying drawings, Figure 1 represents, in perspective, so much of a dash-board as illustrates my improvement of a sole-leather bead-edge or trimming. Fig. 2 shows 20 that portion of the sole-leather bead which is formed over the corner of the dash-frame. Fig. 3 shows a portion of the sole-leather bead as produced with the flange or tongue for the stitching; and Fig. 4, a cross-section of the 25 dash-frame, showing the sole-leather bead-edge or trimming secured thereto.

In the construction of the dash the leathers A are first marked to correspond with the frame B, and then trimmed, when the sole-leather bead-edge C, which constitutes the invention, is put in position with its tongue between the leathers, and there held by suitable cement while being sewed to the leathers. Then the frame is inserted and the inner stitching, d, completes the dash. To properly secure this sole-leather bead-edge by stitching, I make it with an integral flange or tongue, a, which, when the bead is in the position described and shown, is lapped by the edges b b 35 of the leathers above the frame, and the said edges are stitched to the bead through and through said flange or tongue, as shown at c. The sewing being completed, the bead is finished off with polishing-irons, to give it the 40 appearance of the dash-leathers.

It will be observed that the dash-iron is of the simplest form, the sole-leather bead preferably resting upon it, and that the leathers are stitched together inside and outside the 45 frame, and that when stitching them on the out-

side there is secured the hard sole-leather bead-edge by the same stitching operation.

By this improvement the costly dash-rails and the customary stitched-leather border commonly in use are avoided, and the dash formed 55 with a hard and smooth edging, over which the reins play without being worn or wearing the dash-edge.

I am aware that india-rubber, gutta-percha, or like material might be used in place of sole-leather, it being only necessary that the material of which the bead is made should be capable of receiving a polish and of being secured by stitching. I am also aware that this same construction of edging by a hard-leather 65 bead might be advantageously used in other exposed leather edges in carriage-trimming.

The bead may be made by any suitable means to have a suitable tongue or flange integral with it, to receive the stitching. If 70 made of gutta-percha, it may be molded.

The bead-edge or rim is preferably cylindrical in cross-section; but it may be of any suitable form so long as the tongue or flange extends therefrom so as to be overlapped by the 75 dash-leathers outside of the dash-frame, and is of a less thickness than that of said frame.

I have stated that the dash-leathers are secured to the flange or tongue of the sole-leather bead-edge to hold them in position for being 80 sewed, and it will be understood that the leathers and the tongued binding-bead are thus sewed by machine, finishing the work quickly and with little labor. I have also stated that a binder of other material than sole-leather 85 may be used so long as it is capable of being secured by stitching, and it will be understood that such capacity for being stitched refers only to sewing in which the needle makes the hole for the thread through the stitched parts. 90 Metal binders, solid, hollow, and grooved, have been used for vehicle dash-boards. A metal binding bead, rod, or wire has also been used and secured to the dash-leathers by a set-in metal plate having formed holes to receive the 95 stitching; but such binder, when formed with its perforated plate, can only be applied by hand-sewing, slow and difficult by reason of having to match the piercing of the needle with the formed holes in the metal plate. 100

Moreover, such metal binding must be completed the same as the dash-frame before it can be applied to the leathers. It must be made to conform in size and shape to the dash-frame 5 to enable it to be used with such frame. It can only be stitched to the leathers by holding them in position upon the metallic perforated plate during the operation of stitching. In fact, this brass binder is a metallic formed frame.

10 My sole-leather dash-bead gives the advantages of being sewed by machine; of being finished in appearance with the leathers; of being easily and quickly applied to dash-frames of different sizes and shapes; of being glued to the leathers to confine it in position 15 with them for being sewed; of being cheap, desirable, and durable. These things enter largely in the utility of the device, and constitute a substantive improvement in the use 20 of one material over another. These things largely contribute to show that a sole-leather bead - binding having provision for being stitched to the leathers is far in advance of a mere change of material.

I claim—

1. The herein-described improvement in dash-boards for vehicles, consisting of a sole-leather binding or bead-edge of equivalent material, having an integral tongue and stitched to the leathers, substantially as described, for the 25 purpose specified.

2. The combination, with the metallic frame of a vehicle-dash and the covering-leathers therefor, of a sole-leather bead-edge or binding, having an integral flange or tongue stitched 30 to said leathers, and finished to give it the appearance of the dash-leathers, substantially as described, for the purpose specified.

In testimony whereof I have hereunto set my hand in the presence of two subscribing wit- 35 nesses.

JOHN SMITH.
